UNITED STATES PATENT OFFICE.

JOHN E. McCANNA, OF BOUND BROOK, NEW JERSEY.

MOLDING-MACHINE.

SPECIFICATION forming part of Letters Patent No. 598,252, dated February 1, 1898.

Application filed July 30, 1897. Serial No. 646,454. (No model.)

To all whom it may concern:

Be it known that I, JOHN E. McCANNA, a citizen of the United States, residing at Bound Brook, in the county of Somerset and State of New Jersey, have invented certain new and useful Improvements in Molding-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to improvements in molding-machines, and more especially to the molding-machine described in my Letters Patent No. 448,987, granted to me on the 24th day of March, 1891.

20 The object of my invention is to furnish a mechanical rapping attachment and to elevate the molding-flask in both instances by the manipulation of a hand-lever, and I have furthermore separated the pattern-plate into 25 two parts, which latter improvement as the description proceeds will be found to be both useful and labor-saving.

In describing my invention I shall call attention to the accompanying drawings, where 30 like letters of reference indicate corresponding parts in the different views, and I shall only illustrate sufficient of my molding-machine to embody my improvements, as the entire molding-machine and its *modus operandi* 35 have been described in my Letters Patent referred to above and in other molding-machines heretofore.

Figure 1 is a front end view of my machine. Fig. 2 is a side view of Fig. 1. Fig. 3 is a 40 top view of the pattern-plate A and the thereunto-attached spider B, the pattern-plate A having the pattern-rapping cross C pivoted thereto; Fig. 4, a top view of the plate of the molding-machine, and Fig. 5 a top view of the 45 top part of Fig. 1.

Referring to Fig. 1, D is the flask, having lugs D', into which fit pins A', attached to the pattern-plate A.

A is the pattern-plate proper, to which the 50 patterns are attached, and this has by me been constructed with a detachable middle part A², which can be detached and replaced

with a new set of patterns for the following reasons:

It frequently happens in some branches of 55 the hardware trade that a certain number of fixtures have a constant unvarying shape and size. These can be retained on the pattern-plate on the surfaces marked A³ and A⁴ in Fig. 3; but corresponding to these so-called 60 "constants" are certain variables that change from time to time, but must be cast in lots corresponding to the constants in about the proportion shown by the surfaces A³ and A⁴ to A². Formerly the whole pattern-plate as 65 a consequence had to be changed, whereas with my reconstructed pattern-plate the variables can be put on the detachable plate A², which then by suitable means is attached to the pattern-plate A. 70

The pattern-plate A is by four pins E attached to the spider B; but both pieces can be cast as one. The bottom part of the spider B has in a suitable mechanical manner secured to it two vertical rods G, moving up 75 and down in two guides H, bolted to the legs L' and L² of the frame L of the machine, and pivoted to the bottom part of each vertical rod is a link I, each of which is in turn pivoted to a crank-lever K, said crank K being firmly secured to a shaft M, supported in the legs L' and L² of the framework. At one end of said shaft is a hand-lever N, attached to the shaft, by the manipulation of which an up-and-down motion is given to the spider 85 and the pattern-plate through the instrumentality of the above-described means. 80

The upper part of the molding-machine is constructed in the following manner: In order to admit of the four pins E, connecting the 90 pattern-plate A and the spider B, passing through the plate P, said plate P is cut out, as shown in Fig. 4, around each pin E. In order to accomplish one of the objects stated by me, the said plate is furnished with four 95 pins O, adjustably secured in the plate by means of corresponding set-screws Q, which when required will separate the flask D from the pattern-plate. Previous to this operation the pattern-rapping attachment has 100 performed its function in the following manner: Secured to the plate P are four set-screws R, screwed into screw-holes in said plate, having for further security lock-nuts S. On the

tops of these set-screws R rest, respectively, the ends of the four arms C', C², C³, and C⁴ of the pattern-rapping cross C, which cross is pivoted to the pattern-plate. It is now apparent that when the hand-lever N is manipulated so as to elevate the pattern-plate A high enough to permit the arms C', C², C³, and C⁴ of the cross C to be swung in over the tops of the screws R' the pattern-rapping can take place. This simply consists of raising and lowering the hand-lever several times in succession and each time letting the pattern-plate strike on the set-screws R, or, rather, on the cross interposed between said screws and pattern-plate, the operation being equivalent to the one generally performed by the molder when he strikes the flask with a hammer several times, so as to loosen the sand from the surfaces of the patterns. When this rapping has been accomplished, the cross C is swung out of the way—that is to say, the arms are swung away from the top of set-screws R—and if the pattern-plate A is then lowered it will easily be perceived that the flask D, hitherto a component part of the elements that partook of the rapping, will, when met by the four pins O, firmly secured in the stationary machine-plate P, be stopped in its downward movement, and consequently be separated from the pattern-plate A, which was the desired object I had in view.

The stationary part of my machine is consequently the frame L, having the plate P attached at its top on legs L' and L², and the movable part the pattern-plate A, forming one operative piece with the spider B, having attached to it the rods G, connected suitably by intermediate means with the shaft M, operated by the hand-lever N.

What I therefore claim as my invention, and desire to secure by Letters Patent, is—

In a molding-machine, the combination of a flask, a pattern-plate having sectional plates, a pattern-rapping cross pivoted to the under side of said pattern-plate, an upper plate of the molding-machine having four pins adjustably secured to it which pass through the pattern-plate, four set-screws secured in said upper plate to support said cross when in operative position, a spider having the pattern-plate attached to it and having suitable mechanical means secured to it operated by a hand-lever, for the purposes specified, substantially as described.

In testimony that I claim the foregoing I have hereunto set my hand this 28th day of July, 1897.

JOHN E. McCANNA.
